(57) **CLAIM**

The ornamental design for a lens for light detection element as shown and described.

DESCRIPTION

FIG. 1 is a front view of a lens for light detection element of our new design;
FIG. 2 is a rear view thereof;
FIG. 3 is a top plan view thereof;
FIG. 4 is a bottom plan view thereof;
FIG. 5 is a right side view thereof;
FIG. 6 is a left side view thereof;
FIG. 7 is a front perspective view thereof;
FIG. 8 is a rear perspective view thereof;
FIG. 9 is a sectional view taken along the line 9-9 of FIG. 1;
FIG. 10 is a sectional view taken along the line 10-10 of FIG. 1; and,
FIG. 11 is an enlarged view showing a portion of FIG. 10 defined by lines 11-11 and 11'-11'.
